UNITED STATES PATENT OFFICE.

CHARLES RETTIE, OF LIVERPOOL, ENGLAND.

LATCH.

SPECIFICATION forming part of Letters Patent No. 436,435, dated September 16, 1890.

Application filed March 26, 1890. Serial No. 345,357. (No model.)

To all whom it may concern:

Be it known that I, CHARLES RETTIE, of Liverpool, in the county of Lancaster, Great Britain, have invented certain new and useful 5 Improvements in a Combined Door Catch and Lock; and I do hereby declare that the following is a full, clear, and exact description of the invention, which will enable others skilled in the art to which it appertains to 10 make and use the same, reference being had to the accompanying drawings, and to letters of reference marked thereon, which form a part of this specification.

My invention relates to improvements in a 15 combined lock and latch, and is specially designed for use on cupboard and water-closet doors and where there is much jar and vibration, as on board ships.

In its main features this present invention 20 consists of the latch described in the patent granted to me bearing date the 11th day of February, 1890, and No. 420,963, and a locking device, substantially as hereinafter set forth.

25 In the drawings herewith accompanying and making a part of this invention, Figure 1 is a view of a part of a door having my improved lock and latch attached thereto. Fig. 2 is a cross-section of the same. Fig. 3 is a 30 plan of the inside of a door having my latch and lock attached and showing the spring and its recess in dotted lines. Fig. 4 is a section of Fig. 3, taken on line 1 1.

In all said figures same letters refer to like 35 parts.

In the edge of a door is made a recess, and in said recess is pivoted a latch *b*, having a finger *c*, with a beveled edge *d* and handle or knob *e*, which extends outwardly from the 40 outside of the door. At the rear of said latch is a spring, which constantly tends to force the finger of the latch outwardly, so as to engage the casing when the door is closed. Directly behind the said latch in the door is 45 made a recess or well *f*, in which is pivoted a lock-bar *g*, consisting of the body part *h* and the projection *i*, so arranged in said recess that the lock-bar *g* may be revolved or turned to the right or left, so as to allow the latch to 50 be forced back when said projection is turned against either edge *j* of the extension of the re-

cess, as shown in Fig. 1. Over said lock is placed a cover *k*, which holds it in place, and a key *l* passes through the lock-bar. Said key has a handle *m* and extends through the door 55 and terminates in a stem *n*, by which said lock-bar may be operated to lock and unlock the door from the outside as well as the inside. Underneath the lock-bar is made there-in a series of indentations *o*, in which the bent part *p* of a spring *q* plays. By this spring the lock-bar is held firmly in any given position.

The principle involved in this invention is the same whether the lock-bar is inserted in a recess in the face of the door or is contained 65 within a hollow case which is attached to the face or the door.

The operation of my improved lock is as follows: When the latch is unlocked, it operates in the manner set forth in said patent 70 hereinbefore referred to. To lock the door from the inside, take hold of the knob *m* of the key and turn the lock-bar till it reaches the position shown in Fig. 1. To unlock and open the door from the inside, turn the lock-bar till the projection *i* strikes against the edge *j* of the recess *f*. Then with the thumb or finger press the finger *c* of the latch back, the cover *k*, having a slot *r* therein, and open the door. To unlock and open the door from the 80 outside, insert key in the key-hole *s* and turn as before. Then press knob *e* outward and open.

Having thus described my invention and its use, what I claim, and desire to secure by 85 Letters Patent of the United States, is—

1. The combination, with a latch pivoted in the edge of a door and a spring arranged to force said latch outwardly to engage with a clip in the door-jamb, of a plate located behind said latch and having a recess therein to receive said latch when it is drawn back, and a lock-bolt beneath said plate having a spur thereon, and means, substantially as set forth, for revolving said lock-bolt into position which will lock and unlock said latch, as desired, as and for the purposes set forth.

2. The combination, with a latch pivoted in the edge of a door and a spring constantly tending to force said latch outwardly, a lock-bar set in a recess in the face of the door and having a projection thereon, as set forth,

a key whereby said locking-bar may be turned, and a series of indentations in the under face of said locking-bar, of a spring having a bend therein adapted to enter said 5 indentations and hold said locking-bar in any given position, substantially as and for the purposes set forth.

In testimony that I claim the foregoing as my own I affix my signature in presence of two witnesses.

CHARLES RETTIE.
